UNITED STATES PATENT OFFICE.

JOHN R. LONG, OF AKRON, OHIO.

MACHINIST'S VISE.

1,303,693.

Specification of Letters Patent. Patented May 13, 1919.

Application filed August 10, 1918. Serial No. 249,240.

To all whom it may concern:

Be it known that I, JOHN R. LONG, a citizen of the United States, residing at Akron, in the county of Summit and State of 5 Ohio, have invented certain new and useful Improvements in Machinists' Vises, of which the following is a specification.

This invention consists of a machinist's vise having jaws which may be rotated together about a horizontal axis and placed in 10 different angular positions relatively to a split supporting body which is capable of being rotated about a vertical axis or post. Upon bringing the jaws together or in 15 clamping the work therebetween, the split body is clamped to the post and the jaws are clamped against rotation. The split body also has a pair of post openings in angular relation to permit the body to be 20 supported on its side or in an upright position on the post. An operating screw and nuts are employed to bring the jaws together and effect clamping of the jaws in the body and also clamping of the body on 25 the post in the same general way as in the vise shown and described in my Letters Patent No. 1,265,218, of May 7, 1918, and the object of the present invention is to 30 simplify the construction of that form of vise, make it work more effectively, and permit the assembling and separating of its parts with greater convenience and despatch.

In the accompanying drawings, Figure 35 1 is a plan view of my improved vise, and Fig. 2 is a sectional view in a vertical plane centrally through the vise on the line of the jaws. Fig. 3 is a perspective view of the locking cap, and Fig. 4 is a cross section 40 of the vise on line 4—4, Fig. 2. Fig. 5 is a side elevation of the vise, and Fig. 6 is an end view and cross section on line 6—6, Fig. 2. Fig. 6 is a perspective view of the screw-threaded sleeve which receives the 45 operating screw.

The invention comprises a round cast-metal tubular body 2 having a round tubular branch 3 projecting at right angles therefrom, and this branch has a round 50 opening 4 transversely thereof as well as a round longitudinal bore. Moreover, the main body 2 is split transversely opposite the branch 3 and the slot or split 5 extends into the transverse opening 4, thereby permitting the divided portions of the main

body to have a limited movement relatively to each other to the extent of the yield or flexibility afforded in the side walls of the branch at each side of its transverse opening 4. By drawing the split portions of 60 the main body 2 together, it is possible to clamp the body immovably upon a round post 6 and also clamp the round shank 7 of the inner jaw 8 immovably within tubular body 2. A screw 9 is employed to move 65 the outer jaw 10 back and forth relatively to the inner jaw 8, and this screw has a handle 11 at the outside of the movable jaw 10 and is swiveled therein and the flat-sided tubular extension 12 of said jaw has a sliding fit within the shank 7 of the other jaw.

The screw is anchored to the body 2 by a tubular nut 14, an end cap 15, and a knurled ring nut 16 engaged with the outer end of the tubular nut and the end cap. The end 75 cap 15 is interlocked with the jaw shank 7 so as to prevent its rotation independently of the shank, and the tubular nut 14 is interlocked with the end cap to prevent this part from rotating independently. Locking 80 of the end cap is effected by a pair of straight lugs 18 upon its inner face which occupy the end spaces of a rectangular opening 17 in the otherwise closed end of the round shank 7, and locking of the tubular nut 14 is effected by a square collar 19 formed integral with the said tubular nut. A pair of lips 20 on collar 19 bear against 85 the end wall 21 of shank 7, see Figs. 1 and 6, and a slight rotation of ring nut 16 is 90 all that is necessary to bind the parts together so as to work effectively in opening and closing operations of the jaws. In assembling and separating the parts the tubular nut and its collar must be given a quarter turn to place the lips 20 opposite the end spaces of the rectangular opening 17 in the end wall 21 before the tubular nut can be introduced or removed. In this operation, both the end cap 15 and ring nut 16 are 95 either removed or retired, and the square collar 19 is first moved inward and disengaged from the sides of the rectangular opening 17 before a quarter turn is given to the tubular nut 14. In this connection it should be noted that the collar with its lips is of substantially the same rectangular shape and size as the rectangular opening 17 in the end wall of the jaw shank 7 so 100 that the collar may pass through the open-

110

ing when properly alined therewith. Moreover, opening 17 is the same size and shape as the opening within shank 7 which receives the rectangular extension 12 of the outer jaw, thereby simplifying machining operations.

Post 6 is adapted to be secured to a bench or any suitable base 22 by a bolt 23 and nut 24, the head 25 of the bolt being confined 10 within a recess 26 in the upper end of the post immediately beneath the jaw shank 7, and the round flange 27 has a circle of serrations 28 at its bottom adapted to effect a firm hold and grip on the bench and prevent 15 independent rotation of the post.

In operating the vise, when the work is clamped between the jaws the screw 9 draws the tubular nut 14 inwardly and the ring nut 16 presses the end cap 15 against 20 the outer end of the split body while a similar pressing movement occurs in an opposite direction against the other split portion of the body at the annular shoulder 29 at the base of jaw 8, thereby clamping the shank 25 7 in the body and at the same time clamping the split branch 3 of the body on the post. The ring nut 16 may be adjusted to hold the end cap 15 tightly against the end of the body 2 at all times, so that the rotation of 30 the jaws together within the split body may be under frictional restraint, and by reference to Fig. 1 it will be seen that when the nut 16 is tightened the lips 20 of the square collar 19 will draw the shank 7 of jaw 8 toward the end cap 15 while pressing the said 35 end cap against the body 2, and a slight space is left between the outer end of the shank 7 and the end cap 15 so that an effective working union may be obtained.

40 What I claim is:

1. A vise, comprising a split body having a longitudinal bore, a jaw having a shank rotatable in said bore, a second jaw having a flat-sided extension slidable in said shank, 45 an operating screw engaged with said second jaw and extending through said flat-sided collar with a pair of lips, a rectangular opening in one end of said shank adapted to receive said collar and an end wall for said shank adapted to be engaged by said lips, an end cap loosely sleeved on said tubular nut and bearing against one end of said body and having interlocking engagement with said jaw shank, and a nut in 50 screw engagement with said tubular nut and in bearing engagement with said end cap.

2. In a vise as described, a split body having a pair of jaws rotatably mounted therein, one of said jaws having a round shank 60 with a flat-sided opening in one end thereof, and an end cap frictionally engaged with said body having parallel projections occu-

pying said shank opening and locking the shank and cap together.

3. In a vise as described, a split body, a 65 jaw member having a shank with a rectangular opening in one end thereof, an end cap for said body having a locking fit with said shank, a tubular nut having a square collar with lips adapted to pass through 70 said opening and when turned to interlock therewith, a second jaw member, an operating screw engaged with said second jaw member and said tubular nut, and means on the outer end of said tubular nut engaging 75 said end cap.

4. A vise, comprising a tubular body having a branch with a longitudinal bore and a transverse opening and split transversely of the body into said transverse 80 opening, a jaw having a round shank rotatably mounted within the bore of said body, a second jaw having a rectangular extension slidably confined within said shank, an operating screw engaged with said second 85 jaw and extending through said rectangular extension, a tubular nut engaged with said screw having a flat-sided collar of rectangular formation, an end cap sleeved upon said tubular nut in bearing engagement with the end of said split body, a ring nut on the outer end of said tubular nut engaged with said end cap, and both 90 said collar and the end cap having direct locking connection with the said round 95 shank.

5. A vise comprising a split tubular body, a jaw having a cylindrical shank provided with a rectangular opening in the outer end thereof, a cap over the end of said body having 100 projections extending into said rectangular opening, a tubular nut having a collar provided with lips interlocking with the said shank, a nut on the outer end of said tubular nut bearing against the said cap, 105 and a second jaw and an operating screw engaged therewith and in said tubular nut.

6. In a vise as described, an inner jaw having a tubular shank with an inwardly extending wall at its end, a tubular nut having a square collar with lips projecting in opposite direction therefrom and engaged with said wall, an end cap having a central opening bordered on two sides by parallel projections and engaged over the said nut 110 with said shank, an outer jaw and an operating screw through the same and the said nut and cap, and a ring nut on said tubular nut bearing against said cap.

Signed at Akron, in the county of Summit, and State of Ohio, this 6th day of August, 1918.

JOHN R. LONG.
